UNITED STATES PATENT OFFICE.

ISRAEL RUDENSKY, OF NEW YORK, N. Y.

DESIGN FOR A BRACKET FOR SEWING-MACHINE STANDS.

SPECIFICATION forming part of Design No. 29,390, dated September 20, 1898.

Application filed August 27, 1898. Serial No. 689,710. Term of patent 7 years.

To all whom it may concern:

Be it known that I, ISRAEL RUDENSKY, a subject of the Czar of Russia, residing at New York, in the county of New York and State 5 of New York, have invented and produced a new and original Design for Brackets for Sewing-Machine Stands, of which the following is a specification, reference being had to the accompanying drawing, which shows in perspective my newly-designed brace or bracket.

The leading feature of my design consists of a central U-shaped portion, from the ends of which extend lateral arms, each consisting of an arm proper bent at right angles and 15 from which project two parallel horizontal arms, a vertical arm extending downwardly from the central U-shaped portion.

A represents the central portion of the brace or bracket, curved as shown—that is, U-shaped—from which extends downwardly an 20 arm B. From the lower ends of the portion A extend the arms C, bent at right angles, and from each of said arms C extend forwardly the parallel horizontal arms D E.

What I claim is—

The design for a bracket for sewing-machine stands, substantially as herein shown and described.

ISRAEL RUDENSKY.

Witnesses:

GEORGE COOK,
M. VAN NORTWICK.
